(57) **CLAIM**

The ornamental design of a vaporizer cartridge device assembly as shown and described.

DESCRIPTION

FIG. 1 is a front perspective view of a vaporizer cartridge device assembly shown with the vaporizer cartridge removed from the assembly of FIG. 7-13 for clarity of disclosure in accordance with the present invention.

FIG. 2 is a back perspective view of the vaporizer cartridge of FIG. 1.

FIG. 3 is a front view thereof. The back view of the vaporizer cartridge of FIG. 1 is identical to the front view and is therefore omitted.

FIG. 4 is a right side view thereof. The left side view of the vaporizer cartridge of FIG. 1 is identical to the right side view and is therefore omitted.

FIG. 5 is a top view thereof.

FIG. 6 is a bottom view thereof.

FIG. 7 is a front perspective view of a second variation of a vaporizer cartridge device assembly where the vaporizer device body and the vaporizer cartridge are shown in an assembled state of use in accordance with the present invention.

FIG. 8 is a back perspective view of the vaporizer cartridge device assembly of FIG. 7.

FIG. 9 is a front view of the vaporizer cartridge device assembly of FIG. 7.

FIG. 10 is a back view of the vaporizer cartridge device of FIG. 7.

FIG. 11 is a right side view of the vaporizer cartridge device assembly of FIG. 7. The left side view of the vaporizer (Continued)

cartridge device assembly of FIG. 7 is identical to the right side view and is therefore omitted.

FIG. 12 is a top view of the vaporizer cartridge device assembly of FIG. 7.

FIG. 13 is a bottom view of the vaporizer cartridge device assembly of FIG. 7.

FIG. 14 is a front perspective view of a third variation of a vaporizer cartridge device assembly with the vaporizer cartridge removed from the vaporizer body of the vaporizer cartridge device assembly removed from the assembly of FIGS. 7-13 for clarity of disclosure in accordance with the present invention.

FIG. 15 is a back isometric view of the vaporizer cartridge device assembly with the vaporizer cartridge of FIG. 1 removed from the vaporizer body of the vaporizer cartridge device assembly of FIG. 14.

FIG. 16 is a front view of the vaporizer cartridge device assembly with the vaporizer cartridge of FIG. 1 removed from the vaporizer body of the vaporizer cartridge device assembly of FIG. 14.

FIG. 17 is a back view of the vaporizer cartridge device assembly with the vaporizer cartridge of FIG. 1 removed from the vaporizer body of the vaporizer cartridge device assembly of FIG. 14.

FIG. 18 is a right side view of the vaporizer cartridge device assembly with the vaporizer cartridge of FIG. 1 removed from the vaporizer body of the vaporizer cartridge device assembly of FIG. 14. The left side of the vaporizer cartridge device assembly of FIG. 14 is identical to the right side of the vaporizer device of FIG. 14 and is therefore omitted.

FIG. 19 is a top view of the vaporizer cartridge device assembly with the vaporizer cartridge of FIG. 1 removed from the vaporizer body of the vaporizer cartridge device assembly of FIG. 14; and,

FIG. 20 is a bottom view of the vaporizer cartridge device assembly with the vaporizer cartridge of FIG. 1 removed from the vaporizer body of the vaporizer cartridge device assembly of FIG. 14.

The broken lines in the drawings depict portions of the vaporizer cartridge device assembly that form no part of the claimed design.
